UNITED STATES PATENT OFFICE

WASILY WISCHEW AND PETER KOSSOV, OF ST. PETERSBURG, RUSSIA.

SAFETY-LOCK.

SPECIFICATION forming part of Letters Patent No. 665,296, dated January 1, 1901.

Application filed December 14, 1899. Serial No. 740,349. (No model.)

To all whom it may concern:

Be it known that we, WASILY WISCHEW and PETER KOSSOV, subjects of the Emperor of Russia, residing at St. Petersburg, Russia, 5 have invented certain new and useful Improvements in Safety-Locks for Doors and the Like, of which the following is a specification.

Our invention has for its object an improvement 10 in safety-locks of our system, (for which a United States Patent has been applied for on the 28th of December, 1898, Serial No. 700,529.)

The object of this improvement is to insure 15 an absolute impossibility of opening the lock otherwise than by a special key. For this purpose we provide in the barrel or cylinder of our lock spring-pawls, which when the barrel is rotated otherwise than by a special key 20 abut against a stop provided in the chamber which surrounds the said barrel, but when the proper key is applied it forces the spring-pawls to enter in the recesses wherein they are located, so that they will not be arrested 25 by said stop and will permit the entire revolution of the barrel, and consequently the opening of the lock, as will be hereinafter fully explained.

In the accompanying drawings, Figures 1 to 30 7 represent the same views of our lock as in our previous patent application. Fig. 1 is a side view of the lock. Fig. 2 is a front view; Fig. 3, a cross-section; Fig. 4, an end view; Fig. 5, a rear view; Fig. 6, side and end views of 35 the key, and Fig. 7 a section of the pinion on the axle of the cylinder. Fig. 8 represents a cross-section and a side view of the barrel or cylinder provided with safety-pawls. In Fig. 6 the arrangement of the barrel or cylinder 40 provided with safety-pawls in its place in the lock is shown.

a is the cylinder or barrel with projections *x* on its surface; *b*, a pinion on the axis of the cylinder *a*; *c*, a rack on the side of the 45 lock-bolt *g*; *d*, levers; *e*, spindle entering in the lock-bolt *g*; *h*, spring of the levers *d*; *i*, passage or slot for the key *k*; *l*, casing of the lock; *n*, a rod or axis of the levers *d*; *o*, holes for attaching the lock to the door or the 50 like; *p*, a recess in the bolt *g* for the spindle *e*; *t*, a falseway for the key; *A*, a pinion; *B*, curved rod sliding in said pinion; *C*, pin fixed

in the shaft of the cylinder *a*; *D*, spiral spring acting on the rod *B*, and *Z*, cut-out for the stroke of the pin *C*.

55

The cylinder or barrel *a* must make an entire revolution in order to unlock or open the lock. In order absolutely to prevent the possibility of such rotating of the barrel *a* by some other means—for instance, by a metallic 60 wire or thin rod—than a special key *k*, we provide the barrel *a* with transverse recesses, Fig. 8, in which we arrange spring-pawls *a*², pivoted on a shaft or rod *C*² and supported by spiral springs *a*³ in such a manner that 65 one end of each of these pawls projects externally beyond the surface of the barrel *a*. The other end or arm of the pawl *a*² is acted upon by a small rod *a*', also located in the barrel *a* and having its end slightly projecting 70 from the surface of the barrel. The chamber of the casing *l*, Fig. 3, in which the barrel is located, is made eccentric to this barrel and is provided with a stop *l*².

If the barrel *a* be rotated, not by inserting 75 a key *k*, Fig. 6, but some other instrument—for instance, by a thin metallic rod—in the passage *i*, Fig. 3, and should such instrument not be diverted in the falseway *t*, a partial rotation of the barrel *a* could be produced, but 80 the pawl *a*² will surely arrest such rotation as soon as it is stopped at *l*². On the contrary, by inserting the key *k*, in which no hole, such as *x*², is made for the end of the pin *a*', this pin will be depressed (after a partial 85 rotation of the barrel *a*) by the plain portion of the key, causing the pawl *a*² to be turned on its pivot *b*² sufficiently to avoid its meeting with the stop *l*². It is evident that by arranging a number of such pawls *a*² as 90 shown in Fig. 8 this arrangement excludes all possibility of a fraudulent opening of the lock, even if one of these pawls could be occasionally depressed.

We claim as our invention—

95

1. The combination in a lock, of a rotatable cylinder provided with projections on its surface to enter corresponding recesses in a key, and with transverse recesses, of spring-pawls in said recesses, and pins socketed in the cylinder with their inner ends bearing on the pawls and their outer ends projecting beyond the periphery of the cylinder, substantially 100 as described.

2. In a lock the combination with a bolt having rack-teeth, of a cylinder having corresponding teeth for actuating the bolt, said cylinder having transverse recesses, a casing 5 for containing the cylinder eccentric thereto and provided with an interior stop, projections on the cylinder, to engage corresponding recesses in a key, spring-pawl's pivotally seated in the transverse recesses of the bar-
10 rel and pins passing through the cylinder, their inner ends bearing on the pawls and

their outer ends projecting beyond the surface of the cylinder in the path of the key when inserted in the lock, substantially as described.

15 In witness whereof we have hereunto set our hands in presence of two witnesses.

WASILY WISCHEW.
PETER KOSSOV.
